UNITED STATES PATENT OFFICE.

WALTER E. DUNCANSON, OF NEW YORK, N. Y., ASSIGNOR TO THE J. G. WILSON CORPORATION, OF NEW YORK, N. Y., A CORPORATION OF VIRGINIA.

FIRE SHUTTER.

Application filed October 24, 1925. Serial No. 64,539.

This invention relates to automatic fire shutters and more particularly to fire shutters of the type in which the shutter is constructed and arranged to be coiled up on 5 and uncoiled from a rotary roller. In fire shutters of the automatic type the shutter is normally held in open position by mechanism which is operated to release the shutter and allow the same to close the opening 10 in the wall adjacent to which it is placed upon the occurrence of a dangerous rise in temperature.

It is often highly desirable that fire shutters should be arranged so that they may be 15 lowered manually to closed positions without disturbing the devices for holding the same normally in open positions. Such shutters are often closed at night and locked so as to prevent the entrance of thieves or 20 other unauthorized persons into the building and also to prevent or retard the passage of fire through the wall opening. The devices for holding the shutter normally in open position are constructed and arranged 25 to be operated automatically to release the shutter and cause the same to close upon the occurrence of a dangerous rise in temperature and these devices should not be interfered with or disturbed under any circumstances except in testing the automatic 30 operation.

One object of the present invention is to improve the construction and mode of operation of automatic fire shutters and to provide 35 shutters of this type which may be readily opened or closed while the emergency devices for holding the same in open position remain in undisturbed operative condition.

Another object of the invention is to 40 prove and simplify the construction and mode of operation of the devices for holding automatic fire shutters in open position.

A still further object of the invention is to 45 provide an automatic fire shutter which combines the more important features of the underbalanced type of fire shutter constructions and the type in which the shutter is held in open position by means of a counterbalancing spring.

50 With these and other objects in view, one feature of the present invention consists in the provision of a mechanism for holding an automatic fire shutter in open position arranged to be automatically actuated to cause the closing of the shutter upon the

occurrence of a dangerous rise in temperature which will enable the shutter to be readily moved from open to closed position or from closed to open position, while said devices continue in undisturbed operative 60 condition. These devices are preferably arranged to act frictionally on the shutter in holding the same in open position and in closing the shutter it is only necessary to overcome the friction exerted by these devices. The shutter is preferably partially 65 counterbalanced so that a comparatively light frictional force is required to hold the shutter in open position. Thus, in lowering the shutter it is only necessary to overcome this relatively light force.

70 The invention also comprises other novel and improved features, constructions and combination of parts hereinafter described and particularly pointed out in the claims, 75 the advantages of which will be readily understood and appreciated by those skilled in the art.

The invention will be clearly understood from the accompanying drawings illustrating the invention in its preferred form and the following detailed description of the constructions therein shown.

80 In the drawings—

85 Fig. 1 is a view in front elevation of an automatic fire shutter embodying the invention in its preferred form;

90 Fig. 2 is a detail view in front elevation illustrating certain parts of the devices for holding the shutter in open position;

95 Fig. 3 is a detail sectional view taken substantially on the line 3—3 of Fig. 1;

Fig. 4 is a sectional view taken substantially on the line 4—4 of Fig. 1;

100 Fig. 5 is a view in vertical section taken through the left-hand end of the shutter in a plane containing the axis thereof;

Fig. 6 is a view in vertical section illustrating particularly the mechanism for counterbalancing the shutter;

105 Fig. 7 is a detail view taken substantially on the line 7—7 of Fig. 1;

Fig. 8 is a detail view partly in section illustrating certain parts of the mechanism for holding the shutter in raised position;

Fig. 9 is a view similar to Fig. 7 illustrating a modified construction;

110 Fig. 10 is a view in front elevation illustrating a shutter of the form shown in Fig. 9;

Fig. 11 is a detail view in side elevation illustrating the mechanism for retarding the downward movement of the shutter; and

Fig. 12 is a detail view in side elevation illustrating certain parts of the mechanism shown in Fig. 11.

The coiling shutter embodied in the present construction may be of any suitable type such as that made up of jointed metallic 10 slats and is indicated at 2 in the drawings. The shutter is mounted or installed adjacent an opening 4 in the wall 6 of a building to close this opening in the event of fire. The lateral margins of the shutter engage in 15 guides 7 located at each side of the opening 4 and an angle bar 9 is secured to the outer or lower margin of the shutter. The shutter is attached at one end to a rotary barrel or roller 8 and is arranged to be coiled up on 20 and uncoiled from this roller. The roller 8 is rotatably mounted at one end upon a fixed shaft 10 secured in the shutter frame, this shaft engaging in an opening in a disk 12 secured in one end of the roller. The 25 other end of the roller carries a stud shaft 14 secured within the end of the roller and having a reduced portion engaging in a bearing in the shutter frame (see Fig. 6).

The shutter is preferably partially counterbalanced so that a relatively light force 30 is required to hold the same in open position or to close the same against the action of the counterbalancing mechanism. The mechanism for partially counterbalancing 35 the shutter comprises a coiled spring 16, one end of which is attached to the barrel 8 and the other end of which is attached to the shaft 10. The shaft 10 is rotatable in its bearing in the frame and is adjustably held 40 from turning movement by means of a disk 18 secured to the end of the shaft and a pin 20 engaging in an opening in a bracket secured to the frame and arranged also to engage in any one of a series of openings 45 in the disk 18. By a suitable rotary adjustment of the disk 18, the rotary tension of the spring 16 may be readily adjusted for any weight or size of shutter. The spring 16 is preferably formed with its coils 50 out of contact and is attached at its respective ends to the roller 8 and the shaft 10 so that when in an unwound condition, the spring is free from longitudinal tension. Thus there is no frictional contact between 55 the coils of the spring during the rotation of the roller 8 and there is no end thrust produced upon the roller to cause the roller or the parts connected thereto to bind frictionally against the adjacent portions of the 60 shutter frame. Thus a positive and smooth closing operation is made possible as is very desirable in fire retarding shutters.

The mechanism for holding the shutter normally in open position in the present 65 form of the invention comprises a brake

wheel 22 rotatably mounted upon a stud 24 secured in a suitably bent supporting plate 26 embracing the brake wheel and attached to the shutter frame. This brake wheel is connected for rotation with the 70 shaft 14 during the uncoiling of the shutter by means of a pawl 28 pivoted on the wheel and a toothed wheel 30 secured to the end of the shaft 14 and engaged by the pawl. The pawl is held in engagement with the 75 toothed wheel 30 by means of a leaf spring 32 secured to the pawl and engaging a pin 34 secured to the wheel. This connection between the shaft 14 and the brake wheel 22 enables the shaft and roller 8 to rotate independently of the brake wheel and hold the shutter at any point in the opening during the raising of the shutter and also causes the brake wheel to rotate with the shaft and roller when the shutter is lowered. Because of the mounting of the brake wheel 22 on a shaft entirely independent of the shaft 14, the brake mechanism exerts no pressure or strain on the shaft during the 80 operation of the brake and there is no resulting friction which might interfere with the manual coiling and uncoiling of the shutter. 85

The brake wheel 22 is engaged by a brake band 36 secured at one end to a bracket 38 attached to the shutter frame and preferably passing nearly around the brake wheel as shown clearly in Figs. 7 and 9. The brake band 36 is preferably constructed of spring metal and formed so that when released it tends to spring away from the brake wheel 90 so as to allow the brake wheel to rotate. The brake band is held in frictional engagement with the brake wheel with the required pressure by mechanism comprising a lever 40 pivoted at 42 on the shutter frame, one arm of which lever engages in a slot 44 formed in the end of the brake band. The other arm of the lever is acted upon by lever-holding means preferably of a flexible character and comprising a yielding element so that said means will act yieldingly on the lever. Referring particularly to Fig. 7, the latter arm on the lever 40 extends through an opening in the housing in the wall 6 to the outer side of said wall and said lever-holding means is attached to said arm of the lever outside of said wall. Said lever-holding means indicated generally at 46 extends from the lever 40 downwardly about 100 a pulley 48 and then inwardly through a passageway 50 in the wall 6 to the inner side of the wall. From said passageway 50, said lever-holding means extends over a pulley 52 and then downwardly to a point 105 where it is attached to the wall 6 and where it may be conveniently reached for testing. Said lever-holding means comprises a link 54, the upper end of which is engaged in one of a series of openings 56 in the outwardly extending arm of lever 40. Said 110 115 120 125 130

holding means also comprises a series of chain sections 58 and fusible link members 60 and 62, arranged respectively upon the outside and upon the inside of the wall 6. 5 A coiled spring 64 is interposed between two of the chain sections 58 to cause said holding means to act yieldingly on the lever 40. The lower chain section 58 is held in position by inserting the same in a slot in a 10 bracket 66 secured to the inner side of the wall 6. The brake mechanism is set by grasping the lower chain section 58 and pulling the same taut, thereby placing the spring 64 under tension and then inserting said 15 chain section in the notch in the bracket 66. By the tension exerted by the spring 64, the 20 brake band 36 will be yieldingly held in frictional engagement with the brake wheel 22 to hold the shutter in open position. Upon 25 the occurrence of a dangerous rise in temperature, either upon the outside or upon the inside of the wall 6, one of the links 60—62 will be fused, thereby releasing the lever 40 and allowing the brake band to 30 expand and release the brake wheel. Upon the release of the shutter in this manner the shutter will descend to closed position. In testing the shutter, the lower chain section 35 58 is disengaged from the notch in the bracket 66, manually, thus releasing the brake holding power of the same as though the links 60 or 62 had been fused. By engaging the different links of the lower chain section in the notch in bracket 66, the tension 40 under which the spring 64 is placed and the pressure exerted by the brake band upon the brake wheel may be adjusted as desired or required to hold the shutter in open position. The pressure of the brake band upon the brake wheel also may be adjusted by placing the upper end of the link 54 in different openings 56 in the arm of the lever 40, thereby varying the leverage. By thus adjusting the connection between 45 the lever-holding means and the lever 40, the action of the brake mechanism may be readily adjusted for different weights of shutters. Thus, a very heavy shutter may be held in open position in a reliable manner 50 by increasing the leverage.

With the above construction when the brake mechanism for holding the shutter in open position is in operation the shutter may be readily moved to closed position against 55 the action of the brake mechanism. The brake mechanism may be adjusted in the manner above described so as to exert a pressure just sufficient to overcome the overbalancing weight of the shutter when open 60 and the force exerted by the brake is always a yielding force so that a relatively light force is required to move the shutter to closed position. Thus the shutter may be readily closed and may thereafter be raised 65 to open position without disturbing in any

way the mechanism for holding the shutter normally in open position.

Another important advantage secured in the present construction is that the counter-balancing mechanism does not have to be 70 reset after each operation as is the case with certain shutter constructions heretofore extensively employed. The provision of the spring 64 will cause the brake band always to exert a yielding pressure upon the brake 75 wheel regardless of the adjustment of the lever-holding devices.

When the shutter is released the weight of the shutter as stated above, will cause the shutter to descend to closed position. In 80 order to increase the force acting upon the shutter during the first part of its closing movement, a weight bar 68 is mounted with its ends engaging in guides in channel bars 70 by the side of the guides for the shutter to slide vertically in a direction parallel with the shutter, these channel bars being located at opposite sides of the door opening. The angle bar 9 at the lower end of the shutter projects across the path of movement 85 of the weight bar 68, so that the weight bar is engaged and lifted by the shutter during its upward or opening movements. The weight bar also slides upon the guide rods 72, passing loosely through plates 74 secured within the upper ends of the channel bars 70, the downward movement of the guide rods being limited by stop pins 76 passing through the guide rods. The guide rods 72 engage in openings in the ends of the weight 90 bar and the downward movement of the weight bar is limited by means of nuts 78 threaded upon the lower ends of the guide rods. By a suitable adjustment of these 95 nuts the extent of the downward movement 100 of the weight bar may be readily adjusted.

The shutter also is preferably provided with a mechanism for retarding the downward movement of the shutter. In the present form of the invention, the retarding mechanism is similar to that disclosed in applicant's pending application, Serial No. 7,513, filed February 7, 1925. This retarding mechanism comprises a swinging arm 80 pivoted at 82 on the shutter frame and carrying at its lower end an adjustable weight 84 and a pair of pawls 86 and 88 secured rigidly to said arm and arranged to engage a toothed wheel 90 loosely mounted upon the shaft 14. This toothed wheel is connected for rotation with the shaft 14 during the downward movement of the shutter by means of a spring pressed pawl 92 pivoted upon an arm 94 secured to said shaft and arranged to engage the toothed wheel 90 (see Figs. 5, 11 and 12).

As the shaft 14 is rotated during the downward movement of the shutter, the toothed wheel 90 is rotated therewith through the engagement of the pawl 92 130

with said wheel and the swinging arm 80 is swung in opposite directions by the action of said wheel upon the pawls 88 and 86, thereby retarding the downward movement 5 of the shutter. When the shutter is raised the pawl 92 passes idly over the teeth of the toothed wheel 90 so that the retarding mechanism has no retarding effect upon the movement of the shutter.

10 In the construction shown in Figs. 1, 4, 5 and 7, the roller upon which the shutter is coiled, the mechanism for supporting the roller, the mechanism for holding the shutter in open position and the retarding mechanism for the shutter are all installed 15 in an opening 96 in the wall 6 and the shutter is coiled within a casing 98. In the construction shown in Figs. 9 and 10, the devices upon which the shutter is coiled and 20 the retarding mechanism are mounted in a casing 100 upon the outer side of the wall 6. The devices for tensioning the counterbalancing spring are enclosed by a cap 102 secured to this casing and the brake mechanism 25 for holding the shutter in open position is enclosed by a cap 104 secured to the opposite end of said casing. The brake band 36, the lever 40 and the devices acting on the lever 40 to hold the brake band in 30 braking engagement with the brake wheel in the form of the invention shown in Fig. 9 differ somewhat in specific construction and arrangement of parts from the corresponding parts shown in Fig. 7 but have the same 35 mode of operation.

The shutter construction above described combines the advantages of shutters of the counterbalanced or "underwriters" type in which the shutter is held in open position 40 by a counterbalancing spring, and shutters of the underbalanced type. The shutter may be readily opened and closed manually without disturbing the emergency devices for holding the same normally in open position. In 45 testing the shutter, it is only necessary to release the emergency holding devices manually and the parts of the mechanism for holding the shutter in open position may be readily restored to operative condition 50 after testing. This is a great advantage over the counterbalanced type in which the rewinding of the counterbalancing spring and the resetting of the parts after a testing operation requires a great deal of labor 55 and time and considerable skill.

It is to be understood that the invention is not limited to the particular construction and arrangement of parts of the illustrated embodiment of the invention, but that the 60 invention may be embodied in other forms within the scope of the claims.

While certain features of the invention are particularly designed to be embodied in fire shutters of the automatic type in 65 which the shutter is automatically released

and closes upon the occurrence of a dangerous rise in temperature, certain other features of the invention are not limited to automatic fire shutters but may be embodied in fire shutters in which there is no mechanism provided for causing the automatic closing of the shutter. 70

Having explained the nature and object of the invention and having specifically described a construction embodying the invention in its preferred form, what is claimed is: 75

1. An automatic fire shutter mechanism comprising in combination a movable shutter of underbalanced construction, arranged for movement across a wall opening and means comprising an element fusible upon the occurrence of a dangerous rise in temperature for holding said shutter normally in position, said holding means being arranged to allow the shutter to be operated manually by overcoming the action of said holding means while said means remains in operative condition. 80

2. An automatic fire shutter mechanism comprising in combination a coiling shutter constructed and arranged for movement across a wall opening, counterbalancing means for the shutter, and means independent of the counterbalancing means comprising an element fusible upon the occurrence of a dangerous rise in temperature for holding said shutter normally in position arranged to allow while in operating condition the shutter to be operated manually by overcoming the action of said holding means. 90

3. In a fire shutter mechanism having a flexible shutter and rotatable means upon which said shutter may be coiled subject to the influence of a counterbalancing spring, the combination with said shutter and rotatable means of a helical counterbalancing spring formed with its coils out of contact and having one end thereof secured to resist torsion while the other end thereof is attached to and moves with said rotatable means. 105

4. In a fire shutter mechanism having a flexible shutter and a roller upon which said shutter may be rolled, the combination with said shutter and roller of a coiled counterbalancing spring formed with its coils out of contact to reduce friction, said spring having one end secured to resist torsion and its other end connected with the roller so that the rotation of the roller will rotate one end of the spring about the axis of the spring. 110

5. In a fire shutter mechanism having a flexible shutter and a roller upon which said shutter may be coiled, the combination with said shutter and roller of a counterbalancing spring formed with its coils out of contact and attached at one end to the roller 115 120 125 130

- and having its other end secured to resist torsion and substantially free from longitudinal tension when unwound, said spring being connected with the roller so that the 5 rotation of the roller will rotate one end of the spring about the axis of the spring.
6. An automatic fire shutter mechanism comprising in combination a movable shutter constructed and arranged for movement 10 across a wall opening, a brake for holding said shutter normally in position and allowing the shutter to be moved manually by overcoming the action of the brake while the brake is in operation and means for controlling 15 the brake arranged to cause the release of the brake upon the occurrence of a dangerous rise in temperature.
7. An automatic fire shutter mechanism comprising in combination a movable shutter 20 constructed and arranged for movement across a wall opening, a brake for holding the shutter normally in position arranged to allow the shutter to be moved manually by overcoming the action of the brake while the 25 brake is in operation, and means for yieldingly holding the brake in operation arranged to be operated to cause the release of the brake upon the occurrence of a dangerous rise in temperature.
- 30 8. An automatic fire shutter mechanism comprising a coiling shutter constructed and arranged for movement across a wall opening, counterbalancing means for the shutter and yieldingly acting means for holding the 35 shutter normally in position arranged to allow the shutter to be moved manually while said means is in operation, said counterbalancing means being operative when the curtain is released by said holding means.
- 40 9. An automatic fire shutter mechanism comprising in combination a coiling shutter constructed and arranged for movement across a wall opening, means for partially counterbalancing the shutter, and yieldingly 45 acting means for holding the shutter normally in position arranged to allow the shutter to be moved manually and comprising an element fusible upon the occurrence of a dangerous rise in temperature to release the shutter, said counterbalancing means being operative when the curtain is released by said holding means.
- 50 10. An automatic fire shutter mechanism comprising in combination a movable shutter constructed and arranged for movement 55 across a wall opening, means for holding the shutter normally in position, constructed to allow the shutter to be moved manually and arranged to be operated to release the shutter upon the occurrence of a dangerous rise in temperature, and a normally active ratchet 60 for connecting the shutter with said holding means to allow the shutter to be raised freely and to hold the same in partially raised position.
11. An automatic fire shutter mechanism comprising in combination a movable shutter constructed and arranged for movement across a wall opening, means for holding the shutter normally in position comprising 70 a rotary disk connected with the shutter, a brake shoe engaging the disk and means for holding the brake shoe in engagement with the disk to hold the shutter in position arranged to be operated to cause the brake 75 shoe to release the disk upon the occurrence of a dangerous rise in temperature.
12. An automatic fire shutter mechanism comprising in combination a wall, a movable shutter constructed and arranged for movement 80 across an opening in the wall, a friction brake for holding the shutter normally in position arranged when in normal operation to allow the shutter to be moved manually by overcoming the normal action of 85 the brake and means for controlling the brake set in operation to release the brake upon the occurrence of a dangerous rise in temperature.
13. An automatic fire shutter mechanism 90 comprising in combination a movable shutter constructed and arranged for movement across a wall opening, means for holding the shutter normally in position comprising a connector having a yielding element in its 95 length and arranged to be attached at a fixed point to hold the shutter in position and releasable at said point for manual testing.
14. An automatic fire shutter mechanism comprising in combination a wall, a movable shutter constructed and arranged for movement 100 across an opening in the wall, a brake for holding the shutter normally in open position, means for controlling the brake comprising a connector having a yielding element in its length and arranged to be attached at a fixed point to hold the brake 105 in operation, and comprising means fusible upon the occurrence of a dangerous rise in temperature to cause the release of the brake 110 and means for holding said connector under tension arranged to allow its manual release.
15. An automatic fire shutter mechanism comprising in combination a movable shutter constructed and arranged for movement 115 across a wall opening, a friction brake for holding the shutter normally in position, arranged to allow the shutter to be moved manually by overcoming the action of the brake and means for holding the brake in 120 operation arranged to be operated to release the brake upon the occurrence of a dangerous rise in temperature.
16. An automatic fire shutter mechanism 125 comprising in combination a movable shutter constructed and arranged for movement across a wall opening, a friction brake for holding the shutter normally in position, arranged to allow the shutter to be operated manually by overcoming the action of the 130

brake, means for holding the brake in operation arranged to be operated to release the brake upon the occurrence of a dangerous rise in temperature and to be manually operated to release the brake for testing.

17. An automatic fire shutter mechanism comprising in combination a movable shutter constructed and arranged for movement across a wall opening, a friction brake for holding the shutter normally in position arranged to allow the shutter to be moved manually by overcoming the action of the brake and yielding means for maintaining the brake engaged, arranged to be operated to release the brake upon the occurrence of a dangerous rise in temperature.

18. An automatic fire shutter mechanism comprising in combination a movable shutter constructed and arranged for movement across a wall opening, a friction brake for holding the shutter normally in open position arranged when in operation to allow the shutter to be closed manually against the action of the brake and means for holding the brake in operation arranged to be operated to release the brake upon the occurrence of a dangerous rise in temperature.

19. An automatic fire shutter mechanism comprising in combination a movable shutter constructed and arranged for movement across a wall opening, a friction brake for holding the shutter normally in open position, means for holding the brake in operation arranged to be operated to release the brake upon the occurrence of a dangerous rise in temperature and means for connecting the brake with the shutter arranged to allow the shutter to be lifted without actuating the brake.

20. An automatic fire shutter mechanism comprising in combination a movable shutter constructed and arranged for movement across a wall opening, a friction brake for holding the shutter normally in open position, means for holding the brake in operation arranged to be operated to release the brake upon the occurrence of a dangerous rise in temperature, and a ratchet mechanism for connecting the brake with the shutter arranged to allow the shutter to be lifted without actuating the brake.

21. An automatic fire shutter mechanism comprising in combination a movable shutter constructed and arranged for movement across a wall opening, and means for holding the shutter in position, arranged to be operated to release the shutter upon the occurrence of a dangerous rise in temperature, said holding means being constructed to allow the shutter to be operated manually by overcoming the action of said holding means without disturbing the operative condition of said means.

22. An automatic fire shutter mechanism, comprising in combination a movable shut-

ter constructed and arranged for movement across a wall opening, means for holding the shutter normally in open position, comprising a connector having a flexible element in its length and arranged to be attached at a fixed point to hold the shutter in position and releasable at said point for manual testing and fusible means connected with said connector for causing the release of the shutter upon the occurrence of a dangerous rise in temperature.

23. An automatic fire shutter mechanism comprising in combination a movable shutter constructed and arranged for movement across a wall opening, a counterbalancing spring for the shutter, and means independent of the counterbalancing spring for holding the shutter in any position, said holding means being arranged to allow the shutter to be raised or lowered manually while said means remains in operating condition.

24. An automatic fire shutter mechanism comprising in combination a movable shutter constructed and arranged for movement across a wall opening, a counterbalancing spring connected with the shutter to retard the entire descent of the shutter when the shutter is released, and holding means for holding the shutter in any position in which it has been located, said holding means being arranged to allow the shutter to be raised or lowered manually while said means remains in operating condition.

25. An automatic fire shutter mechanism comprising in combination a movable shutter constructed and arranged for movement across a wall opening, a friction brake for holding the shutter stationary in any position in which it is located, arranged to allow, through slippage of the parts of the brake, the shutter to be moved manually while the parts of the brake are in normal operation, and means for releasing the brake upon the occurrence of a dangerous rise in temperature.

26. An automatic fire shutter mechanism comprising in combination a movable shutter constructed and arranged for movement across a wall opening, a friction brake for holding the shutter stationary in position, arranged to allow the shutter to be moved manually, through slippage of the parts of the brake, while the parts of the brake are in normal engagement, and means for causing the release of the brake to allow the shutter to descend, upon the occurrence of a dangerous rise in temperature.

27. A fire shutter mechanism comprising in combination a movable shutter arranged to close a wall opening, counterbalancing means for the shutter, a brake for holding the shutter in position independently of said counterbalancing means, and fusible means to release the shutter upon the occurrence of a dangerous rise in temperature.

28. An automatic fire shutter mechanism comprising in combination, a movable shutter constructed and arranged for movement to open and close a wall opening, constantly operative counterbalancing means for the shutter, a brake for holding the shutter in position, and fusible means to release the shutter upon the occurrence of a dangerous rise in temperature.

10 29. A fire shutter mechanism, comprising in combination a shutter arranged to close a wall opening, frictional means for holding the shutter in position, and counterbalancing

means arranged to act on the shutter independently of said frictional means. 15

30. A fire shutter mechanism comprising in combination a movable shutter constructed and arranged for movement to open and close a wall opening, counterbalancing means for the shutter operative when the shutter is released, and a brake for holding the shutter in position. 20

Signed at New York, New York, this 21st day of October, 1925.

WALTER E. DUNCANSON.
